Primary Examiner — Anhdao Doan*(74) Attorney, Agent, or Firm* — Laurence Greenberg; Werner Stemmer; Ralph Locher(57) **CLAIM**

The ornamental design for a radiography and fluoroscopy system, as shown and described.

DESCRIPTION

FIG. 1 is a front elevation view of the radiography and fluoroscopy system showing my new invention;
 FIG. 2 is a rear elevation view thereof;
 FIG. 3 is a top plan view thereof;
 FIG. 4 is a bottom plan view thereof;
 FIG. 5 is a right elevation view thereof;
 FIG. 6 is a left elevation view thereof; and,
 FIG. 7 is a perspective view thereof.

The broken lines in FIG. 4 are included for the purpose of illustrating portions of the radiography and fluoroscopy system that form no part of the claimed design.
